UNITED STATES PATENT OFFICE

SAMUEL I. BERGER, OF NEWARK, NEW JERSEY

MECHANICAL TOY

Application filed April 15, 1927. Serial No. 183,978.

My present invention relates to mechanical toys and in its most specific application is intended to provide a ludicrous simulation of Noah's ark, although the novel 5 principles of the toy may be applied for simulating other effects.

It is an object of the invention to provide a mechanical toy of distinctly novel appearance of realistic yet fantastic and comical action, which can be produced with parts and stampings of the conventional character ordinarily employed for mechanical toys.

A feature of the invention is to impart movements to a plurality of figures some 15 of which may be animal figures heads extending outward from corresponding windows in the casing, said heads being preferably caused to nod, while the casing in its entirety is caused to rock.

20 Preferably the rocking movement is imparted to the casing by a device intermittently pushing the surface on which the toy rests, the supporting part of the toy being curved for this purpose.

25 Another feature is a figure or head operated from the motor by a sharp nodding action and protruding from the top of the casing and preferably associated with a trap door which is alternately raised and lowered by 30 the movement of the head.

35 Preferably the various figures or heads and the oscillating or pushing device are all operated from a single spring motor within the casing.

40 In the accompanying drawings in which is shown one of various possible embodiments of the several features of the invention.

Fig. 1 is a front elevation of the toy,

45 Fig. 2 is a median vertical sectional view taken longitudinally of the toy,

Fig. 3 is a sectional view taken on line 3—3 of Fig. 1,

Fig. 4 is a sectional view taken on line 4—4 of Fig. 1, and

50 Fig. 5 is a sectional view taken on line 5—5 of Fig. 1.

Referring now to the drawings, I have shown a casing provided with side walls 10 and 11 constituting front and rear panels 55 respectively of the toy, connected by end

walls 12 and a gable roof 13. The side walls have a rocker construction at their lower ends, the lower edge of each of said side walls extending along a continuous curve 14 terminating well beyond the end walls as 55 shown. The device therefor rests upon the table, floor or other support in the manner of a rocking chair.

To the rear of the front wall is a support rod 15 carried in ears 16 struck out from 60 near the ends of said side wall. Pivoted upon said rod in side by side relation are a plurality of figure heads 17, preferably animal heads which may be the familiar inexpensive molded celluloid toys, said heads 65 protruding outward through corresponding windows 18 in the front panel. Midway between the ends of the walls there is pivoted upon a pin 19, supported in an eye 19' in the front panel, a toy human head 20 which in 70 the illustrated embodiment shown would represent Noah. The head of Noah protrudes upward through a rectangular opening 21 in one side of the gable roof which opening is adapted to be closed by a trap 75 door or hatch 22 hinged at the ridge 23 of the roof and closing upon the head 20.

The toy embodies a single spring motor for causing operation of the figures and of the casing in its entirety. The motor is 80 preferably supported by a pair of walls 24 extending transversely between the side walls at a substantial distance from the end walls and serving thereby to brace the structure. The motor is of substantially conventional construction. It is, therefore, 85 briefly noted merely that this motor comprises a spring drum 25 pivoted in the transverse walls, having its helical spring 26 fixed at one end to a gear 27 and at the other to a ratchet wheel 28 cooperating with a ratchet pawl 29 the ratchet wheel being turned by a key 30 accessible from beyond an end wall 12 and formed as an integral 90 part of the support rod 31 for the spring drum. The gear 27 meshes with a pinion 32 upon a crankshaft 33 having bearing supports in the transverse walls 24 and extending well beyond said walls to substanti- 95 100

ally the end walls 12. The motor has the usual intermeshing inertia wheels 34 some on shaft 31 and others on the usual counter-shaft 35.

5 The crankshaft has cranks 36 extending preferably in different planes and aligned with the respective animal figure heads. Each crank is associated with the corresponding animal figure by means of a corresponding link 37 one end of which is formed as eye 38 encircling the corresponding crank arm, and the other end of which has an eye 39 encircling a pin 40 supported at its ends in the sides of the animal figure, and 10 to the rear of the support rod 15.

15 The human figure toy 20 at the roof of the casing is illustratively shown operated from a sharply eccentric drum 41 fixed upon the crankshaft. For this purpose a link 42 is formed with an eye 43 encircling the drum and the other end of said link extends at 45 through a corresponding aperture in the shank 44 of the figure head 20 closely adjacent to the mounting pin 19 therefor. 20 Inasmuch as that toy figure 17 which is substantially directly below the figure toy 20 affords insufficient room for a convenient crank throw it is preferred to operate the same by an eccentric drum 46 similar 25 to drum 41.

30 At the extremity of the crankshaft 33, near one of the end walls 12, I provide a crank arm 50 to the end of which is pivoted a pusher or oscillating rod 51 extending 35 through a corresponding eye 52 fixed preferably near the lower edge of said end wall 12.

35 In operation the motor being wound, and the casing placed upon the floor or table, the 40 operation of the motor will cause the crank-shaft 33 to turn. In its rotation the various crank arms and drum 46 through the associated links 37 will cause the corresponding animal figure heads 17 to nod by pivotal movement about the common support rod 15, 45 the nodding of the various heads being out of synchronism, however, in view of the fact that the crank arms extend in different planes. Simultaneously with the nodding 50 of the figures the head 20 of Noah will be caused to nod sharply by reason of the substantial eccentricity of the drum 41 and the juxtaposition of the end of the link 42 to the mounting pin 19. The trap door 22 55 will alternately rise and drop with the upward and return movement of the head 20. At the same time the motor will cause the push rod 51 to be reciprocated from crank arm 50 through guide eye 52 and to intermittently 60 push against the floor or table, causing the entire device to rock.

65 Thus in operation the toy produces an effect simulating the sharp rocking or swaying of a ship or ark in a stormy sea, while the animal figures nod out of the windows,

and at the same time the figure of Noah or other captain of the ark or ship nods approvingly from the hatch upon his charges.

It will thus be seen that there is herein described an article in which the several 70 features of this invention are embodied, and which article in its action attains the various objects of the invention and is well suited to meet the requirements of practical use.

As many changes could be made in the 75 above construction, and many apparently widely different embodiments of this invention could be made without departing from the scope thereof, it is intended that all matter contained in the above description 80 or shown in the accompanying drawings shall be interpreted as illustrative and not in a limiting sense.

Having thus described my invention what I claim as new and desire to secure by Letters Patent is:

1. In a mechanical toy the combination of a casing having a curved bottom upon which it stands, a motor in said casing, a rod operated from said motor and extending downwardly from near one end of and through said rocking support, means guiding said rod for sliding movement thereof in a nearly vertical line whereby the rod is reciprocated to be caused intermittently to be pushed 95 against the surface on which the toy rests, for rocking the same.

2. A mechanical toy comprising side walls and end walls, a top, a spring motor sustained between said walls, a pair of parallel 100 extensions from the side walls curved at their bottoms and constituting a carrying support for the toy, and a downwardly extending rod near one end of the toy positively reciprocated by said motor, means 105 guiding said rod for sliding movement thereof in a nearly vertical line whereby said rod will intermittently push against the surface supporting the toy thereby causing said toy to rock.

3. A mechanical toy comprising a casing, having a pair of side panels each with a lower curved edge, and end walls connecting said panels, a spring motor confined within said casing and a rod oscillated by said motor, means guiding said rod for sliding movement thereof in a nearly vertical line whereby the rod will be intermittently pushed from near one end of the casing 115 against the support on which the toy rests, 120 thereby cause the toy to rock.

4. A mechanical toy comprising a casing having a pair of side walls each with an elongated curved lower edge end walls connecting said side walls, figure toys protruding outward through corresponding windows disposed in side by side relation at one of said side walls, a spring motor between said side walls, linkage connecting said motor to said figures for causing the latter to 125 130

5. oscillate within said windows, and a downwardly extending rod operated from said motor from near one end of the casing to intermittently push against the surface upon which the casing rests to effect a rocking movement of the casing.

10. 5. A mechanical toy comprising the combination of a casing having a pair of side walls, a pair of end walls, a rocking support for said casing, a figure toy protruding through an opening in said casing, a spring motor in said casing, linkage connecting said motor to said toy for effecting systematic movement of the latter and a push rod reciprocated from said motor and intermittently pushing from near one end of the casing against the surface on which the toy rests, to cause the latter to rock.

15. 6. A mechanical toy comprising the combination of a pair of side walls, a pair of end walls, the lower edges of said side walls extending in a continuous curve for a rocking support of the casing, toy figures protruding through openings arranged in side by side relation in one side wall of the casing, a figure toy protruding outward from the roof of the casing, a single spring motor in said casing, linkage connecting said motor to each of said figures for causing said figures to oscillate, and a downwardly extending push rod operated from said motor to cause the lower end thereof to intermittently engage and push from near one end of the casing against the surface supporting the toy, in order to effect a rocking of the casing in its entirety simultaneously with the oscillation of the figures thereof.

20. 7. A mechanical toy comprising the combination of a wall, a rod extending longitudinally of said wall, a plurality of toy figures pivoted about said rod, each of said figures extending outward from said wall through a corresponding window thereof, a spring motor, a crank rod operated from said motor and extending generally parallel to said rod, and arms extending from various cranks of said arm and connected to said figures to cause said figures to oscillate.

25. 8. A mechanical toy comprising the combination of a wall, a support rod extending longitudinally of said wall, and fixed with relation thereto, a plurality of toy figures pivoted about said rod, each of said figures extending outward from said wall through a corresponding window thereof, a spring motor, a crank rod operated from said motor and extending generally parallel to said support rod, and arms extending from various cranks of said crank rod and connected to said figures to cause the latter to oscillate, said cranks being out of phase relation with each other to cause corresponding non-synchronous operation of said figures.

30. 9. A mechanical toy comprising a pair of side walls, a pair of stays firmly connected

transversely across said side walls, a spring motor supported between said stays, a crank shaft having bearings in said stays and extending therebeyond and rotated from said motor, a support rod sustained in fixed relation parallel to said side walls, figure toys bearing upon said support rod and protruding through corresponding windows in one of said side walls, and links connected to the cranks of said crankshaft at one end and to the respective figures at the other end to cause the latter to oscillate during the operation of the motor.

35. 10. A mechanical toy comprising a wall, a support rod extending parallel to and to the rear of said wall, figure toys pivotally supported upon said rod and extending outward through corresponding windows in said wall, a spring motor back of said wall, a crankshaft having bearing supports and rotated continuously from said spring motor, transverse rods through the respective figures, and links each connected at one end to a crank of the crankshaft and at the other to the cross-rod of the figure toy to cause said figure toys to oscillate during the operation of the motor.

40. 11. A mechanical toy comprising a casing having a top, a trap door at said top, a figure head pivotally mounted below said trap door, a spring motor, a sharply eccentric drum driven from said spring motor and a strap encircling said drum having a link contiguous therewith connected to said figure to cause the latter to oscillate sharply during operation of the motor and by impact with said trap door to cause the latter to rise and fall simultaneously with the movement of said figure head.

45. 12. A mechanical toy comprising the combination of side walls and end walls, said side walls each having a continuously curved lower edge upon which the device is adapted to rock, a spring motor between said side walls, a crankshaft driven therefrom, said shaft terminating near one of said end walls and having a crank arm at the extremity thereof, a downwardly extended rod pivoted to the end of said crank arm, an eye in said end wall through which said rod extends, whereby said rod in the operation of said motor will intermittently engage and push against the surface upon which the toy rests, thereby causing the latter to oscillate.

50. 13. A mechanical toy comprising the combination of a casing having a pair of side walls, each having a continuously curved lower edge upon which the device can rock, a pair of end walls connecting said side walls, a spring motor supported within said casing, a crankshaft extending longitudinally of said casing and driven from said spring motor, a toy figure protruding upward from said casing midway between the

ends thereof, an eccentric device on said crankshaft and a link connecting said eccentric device to said toy figure to cause the latter to oscillate; a crank arm at one end of said crankshaft, a reciprocating rod 5 extending downward from the end of said crank arm and pivoted thereto, a guide for preventing lateral displacement of said rod, said rod intermittently engaging the surface upon which the toy rests, during the operation of the motor and pushing against the same to cause rocking of the toy while the figure oscillates.

14. A mechanical toy comprising the combination of a casing having a pair of side walls, a pair of end walls the lower or supporting edges of said side walls having continuous curved edges upon which the device may rock, a spring motor within said casing, including a crankshaft longitudinally of said casing, a support rod parallel to said side walls, figure toys pivotally mounted upon said rod and protruding through corresponding windows in one of said side walls, links connecting the respective figures to corresponding cranks in said crank arm, said crankshaft having a crank arm near the extremity thereof, a push rod pivoted to said crank arm and extending downward therefrom, and guide means to limit the movement of said push rod to substantially a straight line, whereby in operation of the motor the push rod will intermittently push against the surface on which the casing rests, to cause rocking of the casing in its entirety, while the figures are caused simultaneously to oscillate or nod through the window.

15. A mechanical toy comprising the combination of a casing having a pair of side walls, a pair of end walls, the lower or supporting edges of said side walls having continuous curved edges upon which the device may rock, a spring motor within said casing, including a crankshaft longitudinally of said casing, a support rod parallel to said side walls, figure toys pivotally supported upon said rod and protruding through corresponding windows in said side wall, links connecting the respective figures to corresponding cranks on said crank arm, said crankshaft having a crank arm near the extremity thereof, a push rod pivoted to said crank arm and extending downward therefrom, and guide means to limit the movement of said push rod to substantially a straight line, whereby in operation of the motor the push rod will intermittently push against the support on which the casing rests, to cause oscillation or rocking of the casing in its entirety while the figures are caused simultaneously to oscillate or nod through the window, a sharply eccentric drum between the ends of said rock shaft, a figure head pivoted near the upper end of

said casing and a link including a strap encircling said drum, said link pivoted at its upper end to said figure whereby said figure will oscillate simultaneously with the rocking movement of the toy in its entirety. 70
